LOOSE-LEAF BINDER

Hubert Auburn, Mount Healthy, Ohio, assignor to
 The Tenacity Manufacturing Co., Lockland,
 Ohio, a corporation of Ohio

Application April 21, 1943, Serial No. 483,912

4 Claims. (Cl. 129—24)

This invention relates to loose leaf record books.

An object of the present invention is to provide a loose leaf binder of the record book type, the covers of which are hingedly secured to the back member without resorting to the use of metallic hinges.

Another object of the invention is to provide a loose leaf binder of the record book type with non-metallic cover hinges which are so constructed as to provide a hinge structure which compares favorably with metallic hinges both from a structural and use standpoint.

Still another object of the invention is to provide a loose leaf binder of the record book type having the hereinabove characteristics which may be rapidly and economically manufactured, for the most part, from non-critical materials.

Heretofore it has been common practice in the art of manufacturing loose leaf binders of the record book type to hingedly attach the cover members to the back of a record book by means of metallic hinges, such as, by way of example, are disclosed in the H. Auburn Patent No. 1,891,037, dated December 13, 1932; the E. C. Hazel et al. Patent No. 1,925,719 dated September 5, 1933; or the J. Cooper Patent No. 2,067,846 dated January 12, 1937. Such metallic hinges comprised, broadly speaking, a pair of wing members one of which was secured to or made integral with a metallic back member and the other wing member of which was secured to a cover by means of riveting, or the like, as disclosed in the hereinabove enumerated patents.

The object of the present invention is to provide a loose leaf binder of the record book type in which the number of metallic parts has been reduced to a minimum without sacrificing the desirable structural features which should be embodied in such devices. Devices embodying teachings of the instant invention permit sixty percent of the metal which was formerly used in similar binders to be saved, with a fifty percent reduction in the weight of the finished product.

These and other objects are attained by the means described herein and disclosed in the accompanying drawing in which:

Fig. 1 is an end view of a loose leaf binder of the record book type embodying the teachings of the present invention.

Fig. 2 is a sectional view of the record book of Fig. 1 with the covers in an open or extended position.

Fig. 3 is a perspective view of a loose leaf binder of the record book type with the various

component parts thereof in a separated or spaced-apart relationship for clarity of detail and understanding.

The binder comprises, generally speaking, a back 10, a pair of cover members 11 and a pintle rod assembly 12 which comprises a pair of pintle rod housings 13 secured in spaced parallelism along the opposite edges of attachment plates 14.

With particular reference to Fig. 2, it will be observed that back 10 comprises a wooden form 15 having an inner face 40 and an outer face 41. If desired, form 15 may be fabricated from any other non-metallic material such as, by way of example, plastic, or the like, having due regard for size and shape. A plurality of bolt holes 16 may be drilled or otherwise provided through member 15, said holes being disposed along the longitudinal axis of said member. Preferably, the outer end of each bolt hole 16 terminates in a nut receiving recess 17. Member 15 may be covered with a canvas, denoted generally by the numeral 18, and the canvas may then be covered with leather, or other suitable finishing material denoted generally by the numeral 19. The ends of the covering material may be turned inwardly over inner face 40 of the back form 15 to which it may be secured by means of gluing, tacking, or the like. It will be understood that before applying the canvas and leather coverings to back form 15, a nut 20 will be inserted in each of recesses 17, whereby said nuts will be concealed from view by reason of the canvas and leather covers.

Cover members 11 may likewise be fabricated from suitably shaped core members or cover boards 21 which may be made from wood, cardboard, or other suitable material made up to the desired size and beveled. A heavy piece of canvas 22 may then be glued directly to the inner face of boards 21 with a free edge of canvas projecting forwardly from inner edge 23 of cover board 21. As disclosed in Fig. 3, the width of canvas 22 may be of a dimension considerably less than the width of cover board 21, said canvas extending forwardly from free edge 23 two or three inches.

The outer face of the cover member may then be provided with a suitable finish covering 24 of leather, or the like, which may be glued directly to the cover board. As disclosed in Fig. 3, it will be observed that the ends of the finish covering 24 may be turned forwardly over the ends of the cover boards, and so as to overlie the ends of canvas strips 22, thereby providing a neat durable finished outer edge 42.

After the covers have been lined, gold-tooled, etc., the outwardly projecting free ends of the pieces of canvas 22 and finish covering 24 are laid over and secured to the inner face of back 15 by means of a plurality of tacks denoted generally by the numerals 25. Preferably the tacks are disposed in staggered relationship as disclosed in Fig. 3.

The pintle rod assembly 12 may then be secured to the back member by means of bolts 30 which may be inserted through bolt openings 31 provided in attachment plates 14, and which bolt openings are adapted for alignment with their respective bolt holes 16 provided in back member 15. It will be observed that attachment plates 14 will overlie the heads of those tacks over which they extend thereby effectively precluding accidental and/or unintentional loosening or withdrawal of said tacks from back member 15. In order to further secure the pintle rod assembly to the back member, a plurality of screws 32 (see Fig. 2) may be inserted through suitable openings 33 provided in lower attachment flange or leg 34 of each pintle housing 13 and attachment plates 14, said screws extending through canvas 18, finish covering 19 and projecting into back member 15.

In the preferred embodiment of the invention, attachment plates 14 may be relatively narrow, as disclosed in Fig. 3, in which event it is desirable to provide filler pieces 40 between adjacent attachment plates for the purpose of providing a flat plane surface between the spaced pintle housings 13. If desired, such filler pieces may be fabricated from cardboard, or the like. It is preferable that the outermost row of tacks 25 be aligned so as to be disposed beneath attachment leg 34 of the pintle housing 13 whereby such tacks will at all times be positively held in place. If desired, those portions of canvas 18 and leather 19 which are tacked to back member 15 may be likewise glued thereto, however for strength and durability it is highly desirable that at least one row of tacks be utilized for the purpose of securing the canvas and leather strips to the back member.

It will be observed that covers 11 are thus hingedly secured to the opposite edges of back 10 by means of a hinge comprising a thickness of canvas and a thickness of finish covering. Tests have indicated that such a hinge while considerably lighter in weight than a metallic hinge, is nevertheless quite as satisfactory as a metallic hinge. Such tests likewise indicate that the present hinge will withstand the usual type of service and abuse to which loose leaf binders of the record book type are subjected to for a period of many years, wherefore it is seen that the life of the record book has not been shortened by reason of having dispensed with metallic hinges.

It should be understood that the present invention is not directed to, nor concerned with any particular type of means for actuating the pintle bars 44 which carry pintles 43. Such means may be fully automatic, semi automatic or manual, depending upon the particular usage to which the binder will be put.

What is claimed is:

1. In a loose leaf binder, a back, a pair of covers, and a pintle bar assemblage including transverse attachment plates, said back comprising a wooden form having an inner face and an outer face, a plurality of bolt holes extending through said form, each bolt hole terminating in a nut

5 receptive recess located in the outer face of said form, a nut disposed in each of said recesses, covering material for said form, said material concealing said nuts from view and having its edges turned inwardly over the inner face of said form, each of said covers comprising a core member having front, rear and end edges and inner and outer faces, a width of canvas secured to the inner face of each of said members and along the 10 rear edge thereof with a free edge extending rearwardly of said member, covering material secured to the outer face of each of said members and along the rear edge thereof with a free edge extending rearwardly of said member and with the ends of said material turned over the 15 end edges of said member and over the adjacent end portions of the canvas secured to and carried by the inner face of said member, the free rearwardly extending portions of said cover material and canvas overlying and secured to the inner face of said back to provide flexible hinge 20 connections for the covers, said pintle bar assemblage including a pair of spaced pintle rod housings secured to and carried by the outer edges of the transversely extending attachment 25 plates, said attachment plates including bolt apertures in alignment with the bolt holes provided in said back, bolts extending through said apertures and bolt holes and engaging the nuts located in said nut receptive recesses for securing 30 said pintle rod assemblage to said back.

2. In a loose leaf binder, a back, a pair of covers, and a pintle bar assemblage including transverse attachment plates, said back comprising a wooden form having an inner face and an outer face, a plurality of bolt holes extending through said form, each bolt hole terminating in a nut receptive recess located in the outer face of said form, a nut disposed in each of said recesses, finishing material applied to the outer face of said form for concealing said nuts from view, said material having its edges turned inwardly over the inner face of said form, each of said covers comprising a board having front, rear and end edges and inner and outer faces, a strip of canvas secured to the inner face of each of said boards and along the rear edge thereof, with a free edge extending rearwardly of said board, a strip of finishing material secured to the outer face of each of said boards and along the rear edge thereof with a free edge extending rearwardly of said board and with the ends of said strips turned over the end edges of said board and overlying the adjacent end portions of the canvas secured to and carried by the inner face of said board, the rearwardly extending portions of said finish and canvas strips overlying and secured to the inner face of said back by a plurality of retaining means which extend through said finish and canvas strips and into said wooden form, said pintle bar assemblage including a pair of spaced pintle rod housings secured to and carried by the outer edges of the transversely extending attachment plates, said attachment plates including bolt apertures in alignment with the bolt holes provided in said back, bolts extending through said apertures and bolt holes and engaging the nuts located in said nut receptive recesses for securing said pintle rod assemblage to said back, said finish and canvas strips being disposed between the inner face of said back and said pintle rod assemblage, that portion of said finish and canvas strips between adjacent edges of said back and cover members comprising a hinge connection.

3. In a loose leaf binder, a back, a pair of cover members, and a pintle bar assemblage including transverse attachment plates, said back comprising a wooden form having an inner and outer face, a plurality of bolt holes extending through said form, each bolt hole terminating in a nut receptive recess located in the outer face of said form, a nut disposed in each of said recesses, a covering over the outer face of said form concealing said nuts from view, each of said cover members comprising a board including front, rear and end edges and inner and outer faces, a length of canvas glued to the inner face of each of said boards and along the rear edge thereof with a free edge extending rearwardly of said board, a strip of leather secured to the outer face of each of said boards and along the rear edge thereof with a free edge extending rearwardly of said board and with the ends turned over the end edges of said board and overlying the adjacent end portions of the canvas secured to and carried by the inner face of said board, the free portions of said leather and canvas strips extending rearwardly of said boards overlying and being secured to the inner face of said back by means of a plurality of retaining means which extend through said leather and canvas strips and into said wooden form, said pintle bar assemblage including a pair of spaced pintle rod housings secured to and carried by the outer edges of the transversely extending attachment plates, said attachment plates including bolt apertures in alignment with the bolt holes provided in said back, bolts extending through said apertures and bolt holes and engaging the nuts located in said nut receptive recesses for securing said pintle rod assemblage to said back, said leather and canvas strips being disposed between the inner face of said back and said pintle rod assemblage for providing a flexible hinge connection between adjacent edges of said back and said cover members.

4. In a loose leaf binder, a back, a pair of cover members, and a pintle bar assemblage including

transverse attachment plates, said back comprising a wooden form having an inner and outer face, a plurality of bolt holes extending through said form, each bolt hole terminating in a nut receptive recess located in the outer face of said form, a nut disposed in each of said recesses, a covering over the outer face of said form concealing said nuts from view, each of said cover members comprising a board including front, rear and end edges and inner and outer faces, a length of canvas glued to the inner face of each of said boards and along the rear edge thereof with a free edge extending rearwardly of said board, a strip of leather secured to the outer face of each of said boards and along the rear edge thereof with a free edge extending rearwardly of said board and with the ends turned over the end edges of said board and overlying the adjacent end portions of the canvas secured to and carried by the inner face of said board, the free portions of said leather and canvas strips extending rearwardly of said boards overlying and being secured to the inner face of said back by means of a plurality of retaining means which extend through said leather and canvas strips and into said wooden form, said pintle bar assemblage including a pair of spaced pintle rod housings, each pintle rod housing including a longitudinal attachment flange which overlies and is attached to the outer edges of the transversely extending attachment plates, said attachment plates including bolt apertures in alignment with the bolt holes provided in said back, bolts extending through said apertures and bolt holes and engaging the nuts located in said nut receptive recesses and other means extending through said attachment flanges for securing said pintle rod assemblage to said back, said leather and canvas strips being disposed between the inner face of said back and said pintle rod assemblage for providing a flexible hinge connection between adjacent edges of said back and said cover members.
